US00D612517S

(12) **United States Design Patent**
Nicholson

(10) **Patent No.:** **US D612,517 S**
(45) **Date of Patent:** **** Mar. 23, 2010**

(54) **DOOR**

(75) Inventor: **Jeffery W. Nicholson**, Palmdale, CA
(US)

(73) Assignee: **Anthony, Inc.**, Sylmar, CA (US)

(**) Term: **14 Years**

(21) Appl. No.: **29/333,136**

(22) Filed: **Mar. 3, 2009**

3,911,245 A 10/1975 O'Shaughnessy
3,772,075 A 11/1975 Tarnopol
4,035,608 A 7/1977 Stromquist
4,127,765 A 11/1978 Heaney
4,206,615 A 6/1980 Sobajima
4,248,015 A 2/1981 Stromquist
4,260,876 A 4/1981 Hochheiser

DESCRIPTION

FIG. 1 is a perspective view of the present invention;
FIG. 2 is a front elevational view of the present invention;
FIG. 3 is a left side elevational view of the present invention;
FIG. 4 is a right side elevational view of the present invention;
FIG. 5 is a top plan view of the present invention; with the bottom plan view being a mirror image thereof;
FIG. 6 is a top detailed perspective view of the present invention; and,
FIG. 7 is another top detailed perspective view of the present invention.
